NEEDLE OPERATING MEANS FOR
WARP KNITTING MACHINES

John D. Wenrich, Fleetwood, Pa., assignor to Textile
Machine Works, Wyomissing, Pa., a corporation of
Pennsylvania

Filed Jan. 19, 1966, Ser. No. 521,720
7 Claims. (Cl. 66—86)

ABSTRACT OF THE DISCLOSURE

Operating means for the needles of a warp knitting machine including a first lever on which the needles are mounted, a first link connected to the first lever, a second link connected to the first link, a third link connected to the second link, a second lever connected to the third link, a third lever connected to the second lever, and eccentrics on the drive shaft for operating the first and second cranks.

This invention relates to warp knitting machines and more particularly to improved needle operating means for such machines.

In warp knitting machines and particularly tricot type knitting machines which are operated at high speeds, stitch forming elements including the needles, the presser member for closing the beards of the needles and the sinkers are supported in levers which are operated to move the stitch forming elements along predetermined paths in timed relationship to each other to form stitches of the yarns fed thereto by the yarn guides of the machine. Conventionally, the operating means for the stitch forming elements include either cam operated or eccentric operated linkages connected to the supporting levers for the elements, the latter linkages being found to permit operation of the elements at higher speeds. In the eccentric operated linkages and particularly such linkages for providing the more complex movements of the needles, their operation required the motion of two or more separate eccentric shafts, usually operating at different speeds, or the motion of two or more eccentrics on the same shaft which, combined with the complicated prior arrangements of joints connecting the various members of the linkages, resulted in the development of frictional loads and other forces that limited the operating speed of the machine.

It is therefore an object of the invention to provide means in a warp knitting machine for operating the knitting elements which will overcome the above noted and other objections to prior operating means for such machines.

A further object of the invention is the provision of means in a warp knitting machine for operating the needles of the machine which means includes a single operating shaft having a plurality of eccentric means for operating the needles through linkage having a plurality of individual elements and connecting joints for the elements with each joint connecting no more than two of the individual elements of the linkage.

With these and other objects in view which will become apparent from the following detailed description of the illustrative embodiment of the invention shown in the accompanying drawing, the invention resides in the novel elements and combination of parts in cooperative relationship as hereinafter pointed out in the claims.

In the drawing:

FIG. 1 is an elevational view with parts in section of

2

mechanism for operating the needles of a warp knitting machine in accordance with the invention;

FIG. 2 is a view on an enlarged scale of one of the eccentrically operated members of the mechanism taken on the line and in the direction of the arrows 2—2 of FIG. 3;

FIG. 3 is a view on an enlarged scale taken on the line and in the direction of the arrows 3—3 of FIG. 1;

FIG. 4 is a view on an enlarged scale taken in the direction of the arrows 4—4 of FIG. 1; and

FIG. 5 is a view diagrammatically illustrating the path of movement of the needles along a course which is plotted in relation to the angle of rotation of the operating shaft for the needles.

Referring to FIG. 1 of the drawing there is shown conventional fabricating means of a warp knitting machine including a spring bearded needle 10 which is one of a row of such needles mounted in a bar 11, sinkers 12 in the spaces between the needles, the sinkers being

20 mounted in a bar a portion of which is shown at 15, a presser member 16 for closing the beards of the needles, a bar 17 on which the presser member is mounted, and yarn guides 20 which are mounted for movement through and along the row of needles to lap yarns fed thereby

25 around the needles in the usual manner. The needle bar 11 is supported on levers, one of which is shown at 21, secured to a shaft 22 mounted for rocking movement in a portion 23 of the framework of the machine whereby the needles are adapted to be operated along an arcuate path, indicated diagrammatically at 25, between a low

30 knockover position, as indicated in FIG. 1, to a high position during which time the yarn guides 20 are moved back and forth through the needles to lap the yarn carried thereby around the shanks of the needles below the beards thereof. The needles, after receiving yarn from the guides, are lowered along the path 25 to catch the newly received yarn beneath the beards thereof and the beards are closed by the presser bar 16 until the tips of the beards pass through previously formed stitches in the

35 throats of the sinkers. The sinkers 12 are then retracted to permit the needles to draw yarn for new stitches through the previously formed stitches held on the knock-over surfaces of the sinkers and to cast off or knock-over the latter stitches from the needles. The means for operating the sinkers 12, presser member 16 and guides 20 in the manner set forth forms no part of the invention and is not shown herein.

For moving the needles along the arcuate path in accordance with the invention each of the levers 21 is

50 operated by a linkage including a first link 26 having forked ends, one of the ends being pivotally connected by a pin or stud 27 to the lever and the other end being pivotally connected by a pin or stud 30 to one end of a second link 31. The other or opposite end of the second link 31 is pivotally connected to a pin 32 carried in adjacent ends of a spaced pair of links 35 at opposite sides of the second link. At their other ends the pair of links 35 carry a pin 36 for pivotal connection to the free end of a first rock lever 37 (FIGS. 1 and 4) pivotally mounted

55 on a shaft 40 carried in fixed position in the framework of the machine. Intermediate its ends the second link is mounted for rocking movement on a pin 41 carried in adjacent free ends of a special pair of crank levers 42 (see also FIG. 3). The other ends of the crank levers 42

60 are provided with split type bearing portions 45 for rotatable engagement with spaced eccentric portions 46 of a shaft 47. The shaft 47, which is the main drive shaft of the machine, is rotatably mounted in the framework of the machine and driven by a suitable motor (not shown) in a conventional manner.

65 The links 35 are pivotally connected intermediate their ends to a pin or stud 50 carried in the free end of a

second rock lever 51 positioned between the links. The second rock lever 51 is pivotally mounted on a shaft 52 carried in fixed position in the framework of the machine above shaft 40 and at the same side of the main drive shaft 47 as shaft 40. Intermediate the pin 36 and shaft 40 the first rock lever 37 carries a pin 55 having pivotal engagement with a forked end 56 of a second crank lever 57. At its other end lever 57 is provided with a split type bearing portion 60 for rotatable engagement with an eccentric portion 61 of the shaft 47 intermediate the eccentric portions 46 (FIGS. 2 and 3).

During rotation of the shaft 47 the eccentric portions 46 and 61 combine to operate the various links and levers to move the needles 10 along the arcuate path 25, as shown in FIG. 1 and as indicated in the curve 65 of FIG. 5, from a low position 66 to an intermediate level 67 in which the heads of the needles are slightly above the guide eyes of the yarn guides 20. The needles remain at the level 67 momentarily while the yarn guides are moved back and forth through the needles to lap the yarn carried thereby around the needles after which the needles are raised to a high position 68 to insure that the lapped yarns are around the shanks of the needles below the beard thereof. The needles are then lowered from the high position 68 to the low position 66 to draw yarn for new stitches through the previously formed stitches on the needles and to cast off the latter stitches from the needles as hereinbefore set forth.

From the foregoing it will be seen that the mechanism of the invention is such as to smoothly move the needles in timed relationship to the sinkers, beard presser member and yarn guides to form yarns fed by the guides to the needles into knitted fabric. Furthermore, the arrangement of links and levers and the connecting joints between these members provides an operating linkage for the needles in which the operating forces on the joints are balanced and in which there is a minimum of friction between the joints and members to permit operation of the needles at greatly increased speeds.

It will be understood that the improvements specifically shown and described by which the above results are obtained, can be changed and modified in various ways without departing from the invention herein disclosed and hereinafter claimed.

What is claimed is:

1. In a warp knitting machine having spring bearded needles, a presser member for closing the beards of the said needles, sinkers, and yarn guides for feeding yarns to said needles in combination with means for operating said needles to form said yarns into stitches of a knitted fabric including a first lever on which said needles are supported, a first shaft on which said first lever is supported for movement, a first link having one end con-

nected to said first lever, a second link having one end connected to the other end of said first link, a third link having one end connected to the other end of said second link, a second lever connecting the other end of said third link, a shaft for supporting said second lever for movement, a third lever connected to said third link intermediate the connections thereof with said second link and said second lever, a shaft for supporting said third lever for movement, a drive shaft, a first crank means connecting said drive shaft and said second link, a second crank means connecting said drive shaft and said second lever, and means on said drive shaft for operating said first and second crank means.

2. In a machine according to claim 1 in which said first crank means is connected to said second link intermediate the connections thereof with said first and third links, and said second crank means is connected to said second lever intermediate the connection thereof with said third link and said shaft for said second lever.

3. In a machine according to claim 2 in which said first crank means includes first and second crank members and said first and second crank members are connected to said second link at opposite sides thereof.

4. In a machine according to claim 3 in which said third link includes first and second members, said first and second members being connected to said second link and said second and third levers at opposite sides thereof.

5. In a machine according to claim 4 in which said shafts for said second and third levers are positioned at one side of said drive shaft, said shaft for said second lever being below said drive shaft and said shaft for said third lever being above said drive shaft.

6. In a machine according to claim 3 in which said operating means on said drive shaft comprises separate eccentric means for operating said first and second crank members of said first crank means.

7. In a machine according to claim 6 in which said second crank means is positioned between said first and second crank members of said first crank means and there is eccentric means on said drive shaft intermediate said separate eccentric means on said shaft for said first crank means for operating said second crank means.
